UNITED STATES PATENT OFFICE.

HARRY L. WILSON, OF BOSTON, MASSACHUSETTS.

ACTUATING MECHANISM FOR ROTARY BARBERS' POLES.

1,248,233.

Specification of Letters Patent. Patented Nov. 27, 1917.

Application filed March 28, 1916. Serial No. 87,250.

To all whom it may concern:

Be it known that I, HARRY L. WILSON, a citizen of the United States, residing at Boston, in the county of Suffolk and State of Massachusetts, have invented certain new and useful Improvements in Actuating Mechanism for Rotary Barbers' Poles; and I do hereby declare the following to be a full, clear, and exact description of the invention, such as will enable others skilled in the art to which it appertains to make and use the same.

The invention relates to improvements in rotary barbers' poles.

The object of the present invention is to improve the construction of rotary barbers' poles and to provide a simple, practical, and comparatively inexpensive pole designed for use in barber shop windows and various other places and adapted to be suspended from the top of a window, a ceiling or other supporting means and capable of reverse rotary movement without visible actuating means and of thereby exciting the curiosity and attracting the attention of passers-by and affording an efficient advertising medium.

A further object of the invention is to provide a rotary barber's pole of this character having counter-balancing means for enabling the suspended barbers' pole to be hung with the center of gravity directly below the point of support so that the weight of the suspended parts will operate to facilitate the rotary movement of a device.

Another object of the invention is to provide a hollow rotary barber's pole adapted to contain the actuating mechanism and provided also with a conveniently arranged chamber for the reception of the torsional supporting member when shipping and storing the device and also when the same is not in use to prevent injury to the said torsional member.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from

the spirit or sacrificing any of the advantages of the invention.

55

In the drawings—

Figure 1 is a side elevation partly in section of a rotary torsional barber's pole, constructed in accordance with this invention.

Fig. 2 is an enlarged vertical sectional view of the upper portion of the barber's pole,

Fig. 3 is an enlarged vertical sectional view, the clock motor being shown in end elevation,

65

Fig. 4 is a similar view of the clock motor being shown in side elevation,

Fig. 5 is a horizontal sectional view on the line 5—5 of Fig. 2.

Like numerals of reference designate corresponding parts in the several figures of the drawings.

In the accompanying drawing in which is illustrated the preferred embodiment of the invention, 1 designates a hollow rotary 75 barber's pole designed to be constructed of any suitable material and designed to be provided with spiral stripes for indicating a barber's pole. The hollow body which is cylindrical is provided with upper and lower 80 heads 2 and 3 forming closures for the ends of the hollow body and suitably secured to the same, the upper head being removable to afford access to an upper chamber or compartment 4 designed to receive a torsional 85 suspension member 5 when the barber's pole is not in use and also when it is being stored or shipped. The upper compartment 4 is formed by the said closure and a horizontal partition 6 arranged in spaced relation with the upper end of the hollow body and suitably secured within. The partition 6 and the closures 2 are provided with central vertically aligned openings 7 and 8 through which passes the torsional supporting member 5 which consists of a narrow strip of metal provided at its upper end with a loop or opening 9 for engaging a hook 10 or other supporting means designed to be secured in the top or ceiling of a window or 100 other superimposed supporting surface. The torsional supporting member is preferably attached at its lower end 11 to the frame or casing 12 of a spring motor or clock movement comprising a train of gears 13 actuated 105 by a barrel spring 14 and controlled by an

105

escapement 15 having a verge rod 16 constituting an oscillatory member and extending into a slot or opening 17 of an arm 18 mounted on and carried by the torsional supporting member 5. The arm 18 which is disposed horizontally is preferably provided with a coiled spring 19 suitably secured to the torsional supporting member and constituting a yieldable connection between the horizontal supporting arm and the torsional member. The horizontal arm is preferably formed integral with the coiled spring and the slot of the arm 18 may be conveniently formed by doubling the material and extending one end into the coiled spring. Any other suitable form of slidable or similar connection between the oscillatory arm of the motor and the horizontal arm of the torsional suspension member may of course be employed, and when the horizontal arm is oscillated by the motor the coiled spring forms a yieldable connection and permits the arm to respond prior to the movement of the torsional supporting member, the coiled spring permitting the horizontal arm to respond instantly and at the same time acting upon the torsional supporting member to cause the same to twist horizontally under the action of the spring and the oscillatory arm of the motor. It will therefore, be apparent that through the action of the escapement the torsional supporting member will be alternately twisted in opposite directions and will have its lower supporting portion swung first in one direction and then in the other for rotating the barber's pole or other device. The supporting member 5 may be either a steel ribbon or tape or be made of any other suitable material and the spring motor is suitably secured to the hollow body in the space or compartment 20 below the partition 6 and the hollow cylindrical body is provided at the opposite side of the space or compartment 20 with an adjustable weight 21 adapted to counterbalance the spring motor in order to arrange the center of gravity directly beneath the point of support to secure a perfect operation of the rotary torsional device. The weight 21 which may be constructed of any suitable material is provided with upper and lower attaching flanges or ears 22 and is fastened to the interior of the hollow cylindrical body 1 by screws 23 or other suitable fastening devices. The weight is adjustable both vertically and horizontally and is adapted to cause the barber's pole with the parts carried thereby to hang in a perpendicular position with the center of gravity directly beneath the point of support. By this construction and arrangement the operating mechanism is entirely concealed within the rotary member or hollow cylindrical body and the weight of the same through the momentum attained by the hol-

low body in the rotary movement thereof will assist the operation of the device and the weight may be increased with advantage up to within a safe margin of the breaking points of the various parts. 70 The hollow body is provided with a suitable opening 24 which is practically concealed from view by being formed in one of the stripes of the barber's pole and which is adapted to permit a key to be introduced 75 into the same for operating the winding shaft 25 of the spring motor. In practice, a spring motor will be employed which will require winding but once a week or once in two weeks so that the device will run for a 80 relatively long time without requiring attention. The closure 2 is preferably reduced to form an interiorly projecting portion and a shoulder 27 which is adapted to rest upon the upper end of the hollow body 85 but any other suitable closure may of course be provided for the hollow barber's pole.

It will be apparent that the actuating mechanism for reversely rotating the barber's pole is concealed within the same so 90 that only the suspending supporting tape or torsional member 5 is visible and that the device will therefore excite the curiosity of the public and attract the same thereby rendering the device an efficient advertising medium. While the device is shown in the form of a rotary barber's pole it will be apparent that any form of rotary member may be substituted for the barber's pole.

What is claimed is:— 100

1. A rotary device of the class described including a resilient torsional member, means for attaching the same to a suitable support, a rotary member carried by the torsional member and means contained within the rotary member for alternately twisting the resilient torsional member in opposite directions whereby the rotary member will be reversely rotated. 105

2. A rotary device of the class described including a torsional resilient supporting member arranged vertically and provided at the upper end with means for attaching it to a suitable support, a rotary member carried by the torsional supporting member 115 and means contained within the rotary member for alternately twisting the supporting member in opposite directions whereby the rotary member will be reversely rotated.

3. A rotary device of the class described including a vertically disposed resilient torsional supporting member provided at the upper end with attaching means for securing it to an overhead support, a rotary member into which the said torsional member 125 extends, said rotary member being supported by the torsional member, a motor provided with an escapement and having an oscillatory member and means connected with the escapement and actuated by the 130

oscillatory member for alternately twisting the torsional supporting member in opposite directions to reversely rotate the rotary member.

5 4. A rotary device of the class described including a rotary member having an interior compartment, a motor located within the compartment of the said member and provided with an oscillatory member, a torsional supporting member provided with attaching means and carrying the said rotary member and means actuated by the oscillatory member of the motor for alternately twisting the torsional member in opposite 10 directions.

5. A rotary device of the class described including a rotary member having an interior compartment, a motor located within the compartment of the said member and 20 provided with an oscillatory member, a torsional supporting member provided with attaching means and carrying the said rotary member and means actuated by the oscillatory member of the motor for alternately twisting the torsional member in opposite 25 directions, and a weight mounted within the rotary member and adjustable vertically and horizontally to counter-balance the mo-

tor and maintain the center of gravity of the rotary member below and in alinement with the center of support. 30

6. A rotary device of the class described including a hollow rotary member provided at the upper portion with a partition having an opening, said partition being spaced from the upper end of the rotary member, a removable closure fitted in the upper end of the rotary member and having an opening arranged in alinement with the opening of the partition, a motor secured within the rotary member below the partition and having an oscillatory member, a resilient torsional supporting member secured at its lower end to the motor and extending upwardly through the said openings and provided at the top with attaching means, means actuated by the oscillatory member for alternately twisting the torsional supporting member in opposite directions. 45

In testimony whereof I affix my signature 50 in presence of two witnesses.

HARRY L. WILSON.
